BLOCKER MEANS FOR COIN CONTROLLED MECHANISMS

Harry L. Neer, Beech Grove, and Clifford H. Was-
son, Indianapolis, Ind., and Raymond L. Neer,
Jacksonville, Fla., assignors to Nik-O-Lok Com-
pany, Indianapolis, Ind., a corporation of Indi-
ana

Original application August 6, 1941, Serial No.
405,584. Divided and this application March
25, 1943, Serial No. 480,445

12 Claims. (Cl. 194—1)

This is a division of our co-pending applica-
tion Serial Number 405,584.

The present invention relates to a coin con-
trolled mechanism; and, while the disclosed
mechanism, or parts thereof, may be utilized in
other connections, the invention will be particu-
larly described in connection with coin controlled
locks for doors, or the like.

The field to which the present invention per-
tains is by no means new. For many years, coin
controlled locks have been in use in public toilets,
lavatories, bath houses, and the like; and those
locks have been broadly, quite successful. How-
ever, the locks which have been in use heretofore
have been subject to defects of various types; and
it is the primary object of the present invention
to provide, in mechanisms of the character here
under discussion, a refinement to overcome one
of those defects.

To the accomplishment of the above and re-
lated objects, my invention may be embodied in
the forms illustrated in the accompanying draw-
ings, attention being called to the fact, however,
that the drawings are illustrative only, and that
change may be made in the specific constructions
illustrated and described, so long as the scope of
the appended claims is not violated.

Fig. 1 is a front elevation of the lock of the
present invention in an intermediate stage of
assembly thereof;

Fig. 2 is a similar view of the complete lock
mechanism;

Fig. 3 is a top plan view of the lock mecha-
nism;

Fig. 4 is a side elevation seen from the right-
hand side of Fig. 2, the lock being shown mount-
ed upon a fragment of a door; and

Fig. 5 is a front elevation of a housing for the
lock mechanism.

Referring more particularly to the drawings,
in Fig. 1 we have shown an assembly plate 20
upon which the lock mechanism is built up.
Yokes 21 and 22 having U-shaped portions 23
and 24 are secured to the plate 20 and provide
guides for a latch bar 26 which is slidably sup-
ported on said plate 20.

The latch bar 26 is normally held in projected
position by a spring 31 connected at one end to
a plate 32 suitably secured to the assembly plate,
and at its opposite end to a cotter pin 33 secured
in the latch bar 26.

The latch bar 26 carries an ear 70 in a plane
between the front surface of the assembly plate
and the front surface of a top catch block 71
secured to the assembly plate, said block being

suitably cut away, in the manner most clearly
shown in Fig. 4, for the accommodation of said
ear 70. Threadedly mounted in the block 71 is a
screw 72, most clearly shown in Figs. 1 and 4. In
the projected position of the latch bar 26, the ear
70 is located to the right of the inner end 73
(see Fig. 3) of the screw 72. In the retracted
position of the latch bar, the ear 70 is positioned
to the left of said inner end 73 of the screw.
The part-spherical head 74 of the screw 72 is
formed with a polygonal socket 75 for the recep-
tion of a suitably shaped wrench; and said screw
may be rotated, by operation of such wrench, to
project its end 73 into the path of the ear 70.
10 If the screw is so projected while the latch bar
26 is in the position of Fig. 3, withdrawal of the
latch by operation of either the inner handle or
the outer handle is rendered impossible. If, how-
ever, the latch bar is held in retracted position
15 while the screw 72 is projected into the path of
the ear 70, the latch bar will thereby be retained
in withdrawn position, so that the door will be
freely operable.

Frequently, when a ballroom or banquet hall
25 is rented for a private party, it is desirable to
render pay toilet booths operable without the
deposit of the usual coin; and the mechanism just
above described is provided for that purpose. We
have also provided mechanism whereby, when
30 the latch is so retained in withdrawn position, or
when the latch is so blocked against retraction,
the deposit of a coin by a person desiring to use
the toilet and who has failed to note that the
latch is blocked, is automatically prevented. One
35 arm 76 of a lever 77, pivotally mounted upon
the block 71 by a screw 78, is positioned in the
path of the part-spherical head 74 of the screw
72. As the screw is moved inwardly, the head
74 operates upon the lever arm 76 to swing said
lever in a counter clockwise direction, thereby
moving the depending arm 79 to the right, as
viewed in Fig. 1, to close the coin slot in a man-
ner which will become apparent as the descrip-
tion proceeds.

40 45 Preferably, the screw 72 is formed with a flat
side with which cooperates a ball 80 received
in a bore in the block 71 intersecting the threaded
seat of the screw 72, and urged toward said
screw by a spring 81 backed up by a screw 82.
The latch bar 26 is adapted normally to be
retracted by a coin-receiving arm 101 opera-
tively mounted upon an oscillatable plug 83
adapted to be actuated by a handle 103 jour-
naled in a housing 105 shown in Fig. 5. A mask-
ing plate 102 is formed with a perforation 104

whereby it is pivotally mounted upon a pin 130 carried by a portion 90 moving with the arm 101. As is clearly shown in Figs. 1 and 2, the arm 101 is disposed in the path of the arm 79 of the lever 77 so that, as said lever 77 is moved in a counter clockwise direction from the position of Fig. 1, it will swing the arm 101 in a clockwise direction.

The plate 132 is formed with a coin-receiving slot 133 which, when the parts are in the positions of Fig. 2, registers with a coin-receiving slot 185 formed in the housing 175 to permit a coin to be inserted therethrough into operative relation with the arm 101 to permit the latter to engage the flange 69 on the latch bar 26 to retract the latter.

The casing 175 is further formed with a window 186 with which alternatively register the legends 134 and 135 on the plate 132, depending upon the position of the coin receiver. It will readily be seen that, when the parts are in any positions other than the positions of Fig. 2, the slot 133 in the plate 132 is out of registry with the casing slot 185, whereby said casing slot is masked by a portion of the plate 132 and the insertion of a coin into the mechanism is prevented.

The casing is further formed with a small aperture 187 which, in the assembled condition of the organization, registers with the socket 75 of the screw 72, whereby a polygonal wrench may be inserted to operate the screw 72 without removing the casing 175.

If, for any reason, it is desired to lock the enclosure to prevent access thereto, a polygonal wrench may be inserted through the perforation 187 into the socket 75 in the screw head 74, whereby the screw may be rotated to project the end 73 thereof into the path of the ear 70, whereby retraction of the latch bar will be positively prevented.

In order to prevent a patron from dropping a coin into the slot 185 while the lock is so disabled, we have provided the lever 77 and its associated parts. As has been explained hereinabove, the flared head 74 will act upon the arm 76 of the lever 77, during projection of the screw, to swing said lever in a counter clockwise direction, whereby the arm 79 of said lever will act to swing the arm 101 of the coin receiver in a clockwise direction. Through the action of these parts, the slot 133 is shifted out of coin-accepting registry with the slot 185 very promptly upon initiation of projecting movement of the screw 72, and long before that screw comes into obstructing relation with the ear 70. In the final position of the screw 72, the arm 101 assumes a position such that the two legends 134 and 135 on the plate 132 are both unreadable through the window 186.

If, for any reason, it should become desirable to leave the mechanism in such condition that the door may be opened without actuation of the lock, the attendant will insert a pass key in the lock tumbler 188 to withdraw the latch bar. Now, he may either hold the latch bar in withdrawn position with the latch key, or open the door and hold the latch bar in withdrawn position with his finger, while projecting the screw 72 into the path of the ear 70. In this position, the screw will hold the latch bar in withdrawn position against the tendency of the spring 31. Of course, in this condition of the parts, the slot 185 is masked, by an unperforated portion

of the plate 132, and the legends 134 and 135 are both unreadable through the window 186.

We claim as our invention:

1. In a coin-controlled mechanism, an element to be operated, a coin receiver movable to operate said element, a housing for said mechanism formed with a coin-receiving slot, means associated with said receiver for masking said slot, means operable to block operation of said element, and means automatically operated by operation of said blocking means for shifting said masking means into masking position.

2. In a coin-controlled mechanism, an element to be operated, a coin receiver movable to operate said element, a housing for said mechanism formed with a coin-receiving slot, means shiftable into and out of masking relation with said slot, means shiftable into and out of position to block movement of said element, and means automatically operable by movement of said blocking means into blocking position to move said masking means into masking position.

3. In a coin-controlled mechanism, an element to be operated, a coin receiver movable to operate said element, a housing for said mechanism formed with a coin-receiving slot, means associated with said element and movable therewith between two extreme positions, a member located at a point between said extreme positions and selectively shiftable into and out of the path of said means, means shiftable into and out of masking relation with said slot, and means, automatically operable by movement of said member into the path of said first-mentioned means, to shift said last-mentioned means into masking position.

4. In a coin-controlled mechanism, an element to be operated, a coin receiver movable to operate said element, a housing for said mechanism formed with a coin-receiving slot, means associated with said element and movable therewith between two extreme positions, a member located at a point between said extreme positions and selectively shiftable into and out of the path of said means, projection of said member in one position of said element blocking movement of said element in one direction, and projection of said member in the other position of said element blocking movement of said element in the opposite direction, means shiftable into and out of masking relation with said slot, and means automatically operable by movement of said member into the path of said first-mentioned means, to shift said last-mentioned means into masking position.

5. In a coin-controlled mechanism, an element to be operated, a coin receiver movable to operate said element, a housing for said mechanism formed with a coin-receiving slot, means associated with said element and movable therewith between two extreme positions, a member located at a point between said extreme positions and selectively shiftable into and out of the path of said means, projection of said member into the path of said means while said element is in either of its extreme positions blocking movement of said element toward its other extreme position, means shiftable into and out of masking relation with said slot, and means, automatically operable by movement of said member into the path of said first-mentioned means, to shift said last-mentioned means into masking position.

6. In a coin-controlled mechanism, an ele-

ment to be operated, a coin receiver movable to operate said element, a housing for said mechanism formed with a coin-receiving slot, means associated with said element and movable therewith between two extreme positions, a screw threadedly mounted adjacent said element and shiftable axially into and out of the path of said means at a point between said two extreme positions thereof, means shiftable into and out of masking relation with said slot, a lever pivotally mounted adjacent said screw and having an arm operatively associated with said masking means, and cooperating means associated with said screw and said lever for swinging said lever, upon movement of said screw into the path of said first-named means, to shift said masking means into masking position.

7. In a coin-controlled mechanism, an element to be operated, a coin receiver movable to operate said element, a housing for said mechanism formed with a coin-receiving slot, means associated with said element and movable therewith between two extreme positions, a screw threadedly mounted adjacent said element and shiftable axially into and out of the path of said means at a point between said two extreme positions thereof, said screw being provided with a cam surface, means shiftable into and out of masking relation with said slot, and a lever pivotally mounted adjacent said screw and having an arm operatively associated with said masking means and an arm operatively associated with said cam surface, whereby movement of said screw into the path of said first-named means swings said lever to shift said masking means into masking position.

8. In a coin-controlled mechanism, an element to be operated, a coin receiver movable to operate said element, a housing for said mechanism formed with a coin-receiving slot, means associated with said element and movable therewith between two extreme positions, a screw threadedly mounted adjacent said element and shiftable axially into and out of the path of said means at a point between said two extreme positions thereof, said screw having a flared head, means shiftable into and out of masking relation with said slot, and a lever pivotally mounted adjacent said screw and having an arm operatively associated with said masking means and an arm operatively associated with said flared screw head, whereby movement of said screw into the path of said first-named means swings said lever to shift said masking means into masking position.

9. In a coin-controlled mechanism, an element to be operated, a coin receiver movable to operate said element, a housing for said mechanism formed with a coin-receiving slot, means associated with said element and movable therewith between two extreme positions, a screw threadedly mounted adjacent said element and shiftable axially into and out of the path of said means at a point between said two extreme positions thereof, said screw being provided with a cam surface, means shiftable into and out of masking relation with said slot, and means operatively associated with said cam sur-

face and with said masking means and operated, by movement of said screw into the path of said first-named means, to shift said masking means into masking position.

- 5 10. In a coin-controlled mechanism, an element to be operated, a coin receiver movable to operate said element, a housing for said mechanism formed with a coin-receiving slot, means associated with said receiver for masking said slot, means operable to block operation of said element, means automatically operable by operation of said blocking means for shifting said masking means into masking position, said housing being formed with an aperture smaller than said blocking means, and a removable manipulating element insertable through said aperture and engageable with said blocking means to manipulate said blocking means.

- 20 11. In a coin-controlled mechanism, an element to be operated, a coin receiver movable to operate said element, a housing for said mechanism formed with a coin-receiving slot, means associated with said element and movable therewith between two extreme positions, a screw threadedly mounted adjacent said element and shiftable axially into and out of the path of said means at a point between said two extreme positions thereof, said screw having a flared head, means shiftable into and out of masking relation with said slot, a lever pivotally mounted adjacent said screw and operatively associated with said masking means and with said flared screw head for shifting said masking means, upon movement of said screw into blocking relation with said first-named means, into masking position, said housing being formed with an aperture smaller than said screw head, and a removable manipulating element insertable through said aperture and engageable with said screw head to manipulate said screw.

- 25 12. In a coin-controlled mechanism, an element to be operated, a coin receiver movable to operate said element, a housing for said mechanism formed with a coin-receiving slot, means associated with said element and movable therewith between two extreme positions, a screw threadedly mounted adjacent said element and shiftable axially into and out of the path of said means at a point between said two extreme positions thereof, said screw having a flared head formed in its outer surface with a polygonal socket, means shiftable into and out of masking relation with said slot, a lever pivotally mounted adjacent said screw and operatively associated with said masking means and with said flared screw head for shifting said masking means, upon movement of said screw into blocking relation with said first-named means, into masking position, said housing being formed with an aperture smaller than said screw head, and a removable key including a shaft insertable through said aperture and terminating in a polygonal head cooperatively engageable in said socket to manipulate said screw.
